UNITED STATES PATENT OFFICE.

STANLEY W. NICHOLSON, OF TOLEDO, OHIO, ASSIGNOR TO THE DURA COMPANY, OF TOLEDO, OHIO, A CORPORATION OF DELAWARE.

WEATHER STRIP.

Application filed April 23, 1923. Serial No. 634,132.

This invention relates to weather-strips and relates more particularly to weather-strips for use upon vehicle windows.

It is an object of the invention to provide a weather-strip for a vertically slideable vehicle window which in the raised position of the window closure will establish a seal against admission of moisture to the well or chamber receiving said closure when lowered, said weather-strip having a flexibility permitting a considerable range of location of the closure as regards its raised position and maintaining the seal throughout said range.

The invention consists further in the specific structural features of the improved weather-strip.

In the drawing:—

Figure 1 is a cross-sectional view of a portion of a vehicle window showing the improved weather-strip establishing a seal with the closure of said window in raised position;

Figure 2 is a perspective view of a portion of said strip.

In these views the reference character A designates a vertically slideable vehicle window closure formed by a plate of glass to the bottom edge of which is secured a metallic channel strip B. An edge portion of said channel strip is laterally extended to form a downwardly inclined lip C to co-act with a weather-strip carried by the outside sill member D of the window. Thus, said member has its upper edge portion projecting toward the glass A as indicated at E and to the interior face of said member there is secured a flexible strip F, the upper marginal portion of which forms a flap G normally downwardly inclined.

As the closure A approaches its uppermost limited position, the metallic lip C engages the flexible flap G and forms therewith a weather seal to prevent admission of moisture to the chamber H, entered by the closure A when lowered. The flap G is adapted to yield upwardly responsive to the upward thrust of the lip C so as to maintain engagement with said lip through a considerable range of movement of the closure A so that the latter is not closely restricted as regards its closed position. Thus the closed

position of the member A may be determined by a suitable latch means (not shown) and the flap G will adapt itself to the position of the closure required by said latch means. I designates nails by which the strip F is secured to the interior face of the sill member D.

A feature of the invention is the specific structure of the weather-strip F. Thus, said strip is formed of a fabric member J doubled upon itself and having a layer of rubber K between the two plies of the fabric and another layer of rubber K' upon the exposed face of the strip. The described strip has sufficient stiffness that the flap G will tend always, when released, to return to the normal position shown in full lines in Figure 1. The flexibility of the strip, however, is sufficient that said flap may be raised if necessary to the upper, limiting position indicated in dash lines in Figure 1, in which position said flap engages the projection E of the sill member.

One of the advantages of the described weather-strip is its lack of rebound. That is to say, that the flap G while tending always to return to its normal downwardly inclined position, does not act with sufficient force against the lip C to tend to shift the closure downwardly when the latter is raised to a desired position for latching. Furthermore, the described weather-strip is of inexpensive construction and is adapted to be easily attached. The described strip is considered preferable to one formed entirely of rubber since the fabric reinforces the rubber and prolongs the life of the strip. The rubber is essential, however, both for water-proofing and to give resiliency to the flap.

What I claim as my invention is:

1. The combination with a vertically slideable closure and a weather-strip carried thereby, of a frame member having an upper portion projecting towards said closure, and a weather-strip secured to the interior face of said frame member having a flexible flap formed by its upper portion normally projecting downwardly at an acute angle to the body of the strip for engagement by the weather-strip upon the closure and actuatable by the latter strip between

said normal position and a limiting position of contact with said projecting portion of the frame member.

2. The combination with a vertically slideable closure, and a weather strip carried thereby, of a frame member having an upper portion projecting towards said closure, and a weather strip formed of layers of

rubber and fabric and having a lower portion secured to the interior face of said frame member, and an upper portion projecting towards said closure for engagement by said first mentioned weather strip.

In testimony whereof I affix my signature.

STANLEY W. NICHOLSON.
